UNITED STATES PATENT OFFICE.

VICTOR R. DESPARD, OF HINSDALE, ILLINOIS, ASSIGNOR, BY MESNE ASSIGNMENTS,
TO MCGILL MANUFACTURING COMPANY, OF VALPARAISO, INDIANA, A CORPOR-
ATION OF INDIANA.

MECHANICAL MOVEMENT.

1,425,180.

Specification of Letters Patent. Patented Aug. 8, 1922.

Application filed January 2, 1917. Serial No. 140,248.

To all whom it may concern:

Be it known that I, VICTOR R. DESPARD, a citizen of the United States, residing at Hinsdale, in the county of Du Page and State of Illinois, have invented a certain new and useful Improvement in Mechanical Movements, of which the following is a full, clear, concise, and exact description, reference being had to the accompanying drawings, forming a part of this specification.

My invention relates to mechanical movements and has for its object the provision of improved actuating means for such mechanical movements. My invention is applicable, of course, to a great variety of devices and amongst others it finds particular use in connection with switch movements for electrical devices.

In the application herein I show my invention as particularly applied to a socket for incandescent lamps or plugs, it being of course understood that the description of my invention in connection with this specific form thereof is not intended as a limitation.

In the particular form herein chosen for illustration I provide an electric switch movement of the quick make and break variety which has a lineally movable tension element adapted by succeeding movements in a given direction first to make the circuit and then to break it. My invention concerns itself particularly with means to actuate this tension element. The means which I prefer to employ are adapted for movement in a substantially universal manner and in the preferred form are also adapted for movement lineally.

I will describe this particular form of my invention more in detail, in which—

Fig. 1 is a longitudinal sectional view of a switch movement having my improved actuating means;

Fig. 2 is a top view of a portion of the device shown in Fig. 1;

Fig. 3 is a sectional view on line 3—3 of Fig. 2, and

Fig. 4 is a view similar to that of Fig. 3 showing my actuating device in one of its many actuating positions and showing the switch movement in its alternative position.

Referring more particularly to Fig. 1, I show a socket 10 within which a switch movement is mounted including the movable switch arms 11, 11. These movable switch arms are pivoted at 12 and are electrically

connected together by the bridge piece 13. This bridge piece has what might be broadly termed an H slot 14, the inwardly projecting arms 15, 15 thereof co-operating with the sliding plate 16 and other instrumentalities to confine the movement of the switch device 11, 11. The plate 16 has cut away portions 17, 17 which are deep enough to permit the arms 15, 15 to pass therethrough when said sliding plate 16 is in such position that the cut-away portions 17 are aligned with the arms 15. A plunger 18 having the tail piece 19 is shiftingly mounted in the upturned extremity 20 of the plate 16, a spring 21 normally holding this plunger 18 to the right (Fig. 3). A tension element 22 is secured to the forward end of the plate 16 and a retractile spring 23 restores this plate 16 through the abutments 24. Now whenever the tension element 22 is moved to the right, from the position shown in Fig. 3, then the plunger 18 engages the lower cross-strip of the bridge piece 13 thereby tending to swing the switch element 11 in a contra-clockwise direction. This however is prevented by reason of the fact that the arms 15 rest upon the protruding sides of the plate 16. During this movement of the plate 16 to the right the springs 21 and 23 are of course compressed and the plunger 18 and tail piece 20 are prevented from moving to the right. After a continued movement of the plate 16 to the right sufficient to permit the arms 15 to register with the cut away portions 17 then the tendency on the part of the plunger 18 backed by the spring 21 to throw the switch element in a clockwise direction is permitted to act upon this switch element and the switch element moves by snap action into the position shown by Fig. 4. When the plate 16 is then permitted to retract, due to the action of the spring 23 and the release of the pull upon the tension element 22, the parts move back into the position shown in Figs. 1, 2 and 3, except that the switch element 11 is in the alternative position as shown in Fig. 4. Upon the next forward movement of the plate 16 the plunger 18 would engage the upper cross piece of the bridge 13 and by a similar mode of operation would move the switch element 11 back to its starting position, as shown in Figs. 1, 2 and 3.

My invention concerns itself particularly with means for actuating this tension ele-

ment 22 and the means which I employ consist of an actuating member 25. This actuating member engages the tension member 22 through the agency of the head 26 provided upon this tension member. This head is loosely seated against the shelf 27 provided in this actuating member. Projecting toward the left from this shelf portion is the hood or petticoat 28 which normally abuts the stationary plate 29, upon which all of the actuating parts of the switch are mounted. The actuating member is likewise provided with a forwardly extending hole 30 extending forwardly from the shelf portion 27. It will be seen that in whichever direction this actuating member is moved angularly, using any portion of the periphery of the head 28 as a fulcrum, serves to pull the tension member 22 to the right. The actuating member 25 may be tilted in any direction, as of course readily apparent so that it occupies any conceivable angular position relative to said tension element 22 and in either event this tension member 22 is pulled to the right. Furthermore, this actuating device 25 may be moved to the right, as shown by the dotted lines of Fig. 2, so as to actuate this tension member 22 by direct linear pull. When I use the term linear pull herein and in the claims, I of course do not mean that it is necessarily in an absolutely straight line, because a pull exerted toward the right upon this actuating member 25, even though the pull were not exactly in a straight line would yet pull the tension member 22 to the right, even though the actuating member were tilted slightly. In the normal condition of operation, however, it is assumed that there will not be direct pull as often as there would be a use of this actuating device 25 in the manner shown in Fig. 4, wherein the periphery of the hood portion 28 is used as a fulcrum. It will likewise be seen that this actuating member 25 may, if desired, have a pull chain 31 attached and the tension member 22 will be actuated whatever may be the direction of pull exerted upon the actuating device 25 by the chain 31. This chain 31 may desirably be held in place by having one of its balls confined within the fingers 32 of the split catch 33, the particular form herein contemplating that the ball is inserted between the finger pieces 32 before the catch 33 is inserted in place in the actuating device 25. This catch 33 by reason of its split character permits the fingers 32 to be separated for the purpose of introducing the ball of the chain 31. I likewise prefer to insert a plug of insulation 34 between the head 26 and any part metallically connected with the chain so that there is an absolute insulating effect between any part of the chain and any part of the switch movement. Of course, any other suitable means other than the plug 34

would accomplish this same result. The universal nature of my actuating device will thus be readily clear.

A movement of the actuating device 25 of the structure herein shown into any position other than the normal position causes an actuation of the switch movement. The actuating element is universally movable, using any part of its inner hood as a fulcrum, and further than this, is so mounted that it may by direct pull actuate the switch device.

In the claims I use the term lever to of course include cams, toggles, or other equivalent actuating elements.

From what has been thus described the nature of my invention will be readily clear to those skilled in the art.

Having however thus described one form which my invention may take, what I claim as new and desire to secure by Letters Patent is:

1. In a device of the character described, the combination of a snap-action switch having cooperating switch elements, and a lever universally operable for effecting such action of the switch elements.

2. In a device of the character described, the combination of cooperating switch elements, a universally movable lever having a self assuming neutral position, and control means including said lever for effecting a snap-action cooperation of said switch elements upon operation of the lever from its neutral position.

3. In a device of the character described, the combination of cooperating switch elements, and control means including a universally movable lever for effecting a snap-action cooperation in both closing and opening said switch elements.

4. In a device of the character described, the combination of a snap-action switch having cooperating switch elements, and control means therefor including a lineally and tiltably movable actuating device either such movement of which will effect said snap-action cooperation of the switch elements.

5. In a device of the character described, the combination of cooperating switch elements, and control means including a normally neutral device operatively connected with the switch elements and manually tiltable in a plurality of different planes for effecting a snap-action cooperation of said switch elements.

6. In a device of the character described, the combination with a movable switch element adapted to successively occupy alternative resting positions, of means including a universally movable lever adapted by successive actuation from its neutral position to successively move said element into its alternative positions.

7. In a device of the character described,

the combination with a movable switch element adapted to successively occupy alternative resting positions, of means including a universally movable lever adapted by successive actuation from its neutral position to successively move said element into its alternative positions by snap action.

8. In a device of the character described, the combination with a movable switch element adapted to successively occupy alternative resting positions, of control mechanism including universally movable means adapted by successive actuation from its neutral position to successively move said element into its alternative positions.

9. In a device of the character described, the combination with a movable switch element adapted to successively occupy alternative resting positions, of control mechanism including universally movable means adapted by successive actuation from its neutral position to successively move said element into its alternative positions by snap action.

25 10. In a device of the character described the combination with a movable switch element, of control mechanism including universally movable means for causing snap action movements of said element for both closing and opening the switch element.

11. In a device of the character described, the combination with a movable switch element adapted to successively occupy alternative resting positions, of means including a universally movable lever adapted by successive actuation from its neutral position to successively move said element into its alternative positions, said means retaining said element in the particular resting position into which it was last moved regardless of the return to neutral position of said lever.

12. In a device of the character described, the combination with a movable switch element adapted to successively occupy alternative resting positions, of means including a universally movable lever adapted by successive actuation from its neutral position to successively move said element into its alternative positions by snap action, said means retaining said element in the particular resting position into which it was last moved regardless of the return to neutral position of said lever.

55 13. In a device of the character described, the combination with a movable switch element adapted to successively occupy alternative resting positions, of control mechanism including universally movable means adapted by successive actuation from its neutral position to successively move said element into its alternative positions, said

mechanism retaining said element in its last actuated resting position regardless of the return to neutral position of said means.

14. In a device of the character described, the combination with a movable switch element adapted to successively occupy alternative resting positions, of control mechanism including universally movable means adapted by successive actuation from its neutral position to successively move said element into its alternative positions by snap action, said mechanism retaining said element in its last actuated resting position regardless of the return to neutral position of said means.

15. In a device of the character described, a lamp socket including a base and shell, a snap-action switch carried by the base within the shell, a universally movable device supported so as to protrude from the side wall of the shell, and operating connections between said switch and device.

16. In a device of the character described, a lamp socket including a base and shell, cooperating switch elements carried by the base within the shell, and means including a universally movable lever protruding from the side wall of the shell operatively connected for effecting a snap-action cooperation of opening and closing of the switch elements.

17. In a device of the character described, a lamp socket including a base adapted for insertion in a shell, switch mechanism carried on the base, a universally mounted lever carried with the base adapted to protrude through the side wall of the shell, and operating connections between said switch and lever.

18. In a device of the character described, a frame, contact operating switch mechanism carried by the frame, a lever connected with said mechanism and having a peripheral edge riding on the frame so as to permit a universal tilting thereof and effect a linear movement of the connection to operate the switch mechanism.

19. In a device of the character described, a frame carrying a switch, a plate carried by the frame, a lever having a peripheral edge abutting said plate, an operating connection between said lever and switch extending through said plate, said lever being universally supported and movable on the peripheral edge for operating the switch.

In witness whereof, I hereunto subscribe my name this 26th day of December, A. D., 1916.

VICTOR R. DESPARD.
